William F. Reid.

UNITED STATES PATENT OFFICE.

ALEXANDER L. W. BEGG, OF NEW YORK, N. Y.

WHEEL.

1,242,641.

Specification of Letters Patent.

Patented Oct. 9, 1917.

Application filed September 26, 1916. Serial No. 122,183.

To all whom it may concern:

Be it known that I, ALEXANDER L. W. BEGG, a citizen of the United States, and a resident of New York, in the county of New York and State of New York, have invented certain new and useful Improvements in Wheels, of which the following is a specification.

The object of the present invention is to provide an improvement in the construction of wheels used on vehicles of various forms, in which the tread member is not itself of a resilient character, but is connected with the inner portion of the wheel by means that will furnish the desired high degree of resiliency; whereby a large amount of flexibility as well as elasticity is produced; and where the resilient member is formed of a pneumatic device, the puncture and injury of such member is avoided.

In the drawing illustrating embodiments of my invention, Figure 1 is a transverse section taken radially through the half portion of the wheel. Fig. 2 is a section showing one of the disks and the ring member passing therethrough. Fig. 3 is a fragmental sectional view of some of the parts shown in Fig. 1. Fig. 4 shows a fragmental elevation, partly broken away of a modification. Fig. 5 is a transverse radial section reduced of the structure of Fig. 4, and Fig. 6 shows another modification.

This invention comprises essentially a hub, a road-engaging member that is preferably of a form semi-circular in cross-section and suitably connected with the hub at its side edges; while inside of the road-engaging member are located a large number of tread members of a cylindrical nature that are apertured, and through all of which passes a circumferentially extending member of a ring form; the disks being movable inwardly toward the axis but sliding on the ring member.

In the arrangement shown in Figs. 1, 2 and 3, I provide a hub V to which is suitably secured a pair of side plates D—D. To the outer edges or margins of the plates D is secured a road-engaging member in the form of a shoe S semi-circular in cross-section that may be formed of a rubber fabric such as is used on pneumatic tires for the outer member, and which is shown as secured by bolts m.

Between the inner margins of the side

plates D is secured an annular structure A semi-circular in cross-section of suitable airtight fabric such as rubber cloth, that will form a pneumatic chamber B with the side plates D that can be controlled by a valve K.

The shoe S and the fabric A thereby enclose a chamber that is circular in section, in which is placed a series of disk members C. These disks have an aperture F of a rectangular form as shown in Fig. 2. To impart suitable rigidity to the disks and yet permit their free inward movement when the shoe strikes an obstruction, I provide a circumferentially extending annular member such as a ring R passing through the apertures F as clearly shown in Figs. 1 and 3.

It is also desirable to provide truss members extending across between the margins of the side plates D and as shown I provide a series of bars T extending across that may be secured to plates D by the bolts m. If desired the ring R may be secured to the bars T by bolts e as shown to furnish greater strength and solidity.

With this arrangement it will be seen that when the shoe S is depressed by engaging with the road or an obstruction the adjacent disk C will be deflected toward the hub and tend to assume the position indicated by the circle A'. This will cause an inward deflection of the fabric A and thereby compress the air chamber and bring the resiliency thereof into action.

It will be understood that the disk will slide on the ring R at its aperture F to assume this position and when the pressure is removed on the tread the disk will be forced back to its former position and restore the shape of the shoe. It will be understood that the cross bars T extend free between the disks and will not interfere with the radial movement.

In the modification shown in Figs. 4 and 5, I provide a somewhat similar arrangement of hub V', side plates D', shoe S', disk C', and ring R'. Instead of the pneumatic chamber I provide radial extending coil springs on their outer end engaging an articulated band d that is pressed by the springs against the series of disks C'. In this arrangement the compression of the shoe will move one or more disks inwardly that will slide on the ring R' and deflect the band d to compress one or more of the

springs N. This produces the same effect as in the other form without the employment of an air chamber.

Another modification is shown in Fig. 6
5 in which disks C² are placed between a shoe
S² and a pneumatic chamber W. The disks
in this form extend circumferentially and
each has two apertures F² and are shown
10 as arranged in a double row in staggered
form. In this structure the circumferen-
tially extending ring member is in the form
of a coil R² that passes around the air cham-
ber W and through the apertures F² of the
15 disks. The operation of this arrangement
is similar to that of the other forms de-
scribed. Compression of the tread will move
the disks inwardly to compress the air cham-
ber, the disks sliding on the ring member.

Having thus described my invention, what
20 I claim is:—

1. A wheel comprising a hub, a pair of
side plates, an air-tight fabric connecting
the margins of the plates and extending in-
wardly whereby to constitute an annular
25 closed chamber, and a tread portion formed
of a series of independently movable loop
members of a cylindrical form that engage
said fabric portion and project beyond the
side plates.

30 2. A wheel comprising a hub, a pair of
side plates, an air-tight fabric connecting
the margins of the plates and extending in-
wardly whereby to constitute an annular
35 closed chamber, a tread portion formed of
a series of independently movable loop mem-
bers of a cylindrical form that engage said
fabric portion and project beyond the side
40 plates, and a circumferentially extending
ring member projecting through the said
loop members.

45 3. A wheel comprising a hub, a pair of
side plates, an air-tight fabric connecting
the margins of the plates and extending in-
wardly whereby to constitute an annular
closed chamber, a tread portion formed of
a series of independently movable members
of a cylindrical form that engage said fab-

ric portion and project beyond the side
50 plates, a series of bars connecting the edges
of the plates, and a circumferentially ex-
tending ring member located between the
bars and the inner part of the tread por-
tion and rigidly secured to the bars.

4. A wheel comprising a hub, a pair of
55 side plates, an air-tight fabric connecting
the margins of the plates and extending
inwardly whereby to constitute an annular
closed chamber, a tread portion formed of
a series of independently movable loop
60 members of a cylindrical form that engage
said fabric portion and project beyond the
side plates, a series of bars connecting the
edges of the plates, and a circumferentially
extending ring member located between the
65 bars and the inner part of the tread por-
tion and projecting through the loop mem-
bers.

5. A wheel comprising a hub, an annular
compressible air chamber, a tread portion
70 formed of a series of independent disks
that engage the air chamber, a ring member
passing through said disks to permit inde-
pendent movement of such members on in-
ward deflection, and a road-engaging mem-
75 ber of fabric inclosing said disks.

6. A wheel comprising a hub, a resilient
supporting member connecting with the
hub, a tread portion engaging the resilient
member and formed of a series of independ-
80 ent disks, an annular member projecting
through said disks permitting inward de-
flection thereof, and a road-engaging
member of fabric engaging the disks.

7. A wheel comprising a hub, a pair of
85 side plates, a road-engaging member of fab-
ric secured to the margins of said plates,
a series of apertured disks engaging the
inner face of said fabric, resilient means be-
tween the disks and the hub permitting in-
90 ward deflection of the disks independently,
and a circumferentially extending ring
member projecting through all of said disks
to permit said movement of the disks.

ALEXANDER L. W. BEGG.
